(57) **CLAIM**

The ornamental design for a karaoke audio and multimedia player, as shown and described.

DESCRIPTION

FIG. 1 is a perspective view of karaoke audio and multimedia player showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlarged view of its FIG. 1.

The broken lines illustrate portions of the karaoke audio and multimedia player that form no part of the claimed design. The dot-dash broken lines indicate cutoff boundaries for enlarged detail portion views and form no part of the claim.
